ORNAMENT FOR AN AUTOMOBILE HOOD

Clifford C. Voss, Clawson, Mich., assignor to Chrysler Corporation, Highland Park, Mich., a corporation of Delaware

Application May 12, 1953, Serial No. 24,986

Term of patent 14 years

(Cl. D14—18)

To all whom it may concern:

Be it known that I, Clifford C. Voss, a citizen of the United States, residing in the city of Clawson, county of Oakland, and State of Michigan, have invented a new, original, and ornamental Design for an Ornament for an Automobile Hood, of which the following is a specification, reference being had to the accompanying drawings, forming part thereof, in which:

Fig. 1 is a side elevational view of an ornament for an automobile hood showing my new design;

Fig. 2 is a top plan view thereof;

Figs. 3 and 4 are sectional views taken on the lines 3—3 and 4—4 respectively of Fig. 2;

Figs. 5, 6 and 7 are sectional views taken on the lines 5—5, 6—6 and 7—7 respectively of Fig. 1; and

Figs. 8, 9, 10 and 11 are sectional views taken on the lines 8—8, 9—9, 10—10 and 11—11 respectively of Fig. 2.

I claim:

The ornamental design for an ornament for an automobile hood, substantially as shown.
